UNITED STATES PATENT OFFICE.

FRANCESCO RENZO, OF PATERSON, NEW JERSEY.

SHUTTLE-TENSION DEVICE

Application filed December 27, 1926. Serial No. 157,053.

This invention relates to tension devices for shuttles of the class in which, in cooperation with a row of fixed pins or guides in the shuttle, is employed a lever having guides and normally spring held in a position where the thread, extending through both sets of guides, is normally maintained in zig-zag form, the bends therein tending to become straightened when the thread is subjected 5 to a pull and the lever is consequently moved to bring its guides into alignment with the fixed guides. In one form of lever for such devices the guides are held thereon by forming at intervals in the flat shank of the 10 lever sets of twin-pairs of holes, and then threading a cord or string through the twin-pairs one after another and through the (loop- or ring-shaped) guides in such manner that between each two pairs of holes formed 15 by twin-pairs a guide will be bound to the shank. The holes are necessarily small, therefore limiting the gage of the cord or thread and making it a tedious operation to assemble the device. Again, the guides have 20 no means but the binding effected by the string or cord and such shellacing as the device usually undergoes as the final step in the assembling to keep them fixed and in upright position on the shank. The object 25 of this invention is therefore to improve tension devices of the class indicated in these respects.

In the drawing,

Fig. 1 is a fragmentary plan, partly in section, of a loom shuttle embodying my invention;

Fig. 2 is a top plan of the improved tension lever;

Fig. 3 is an underneath plan view thereof;

Fig. 4 is a horizontal fragmentary top plan view, showing the guides in horizontal section;

Fig. 5 is a sectional view on the line 5—5, Fig. 3; and

Fig. 6 shows a slight modification.

In a cavity 1 in the shuttle 2 is arranged the mentioned line of fixed pins or guides 3. 4 is the pin affording the fulcrum for the improved tension lever; 5 the elastic band for holding the same in the retracted position, and 6 is the rotatively adjustable pin to which one end of the band is fastened as usual.

The lever proper 7 takes the usual form of tension levers used in this class in which the thread guides are secured thereto by a

cord, string or other flexible device in that it consists of a strip of flat metal having a straight shank 8 and one end bent to form a bearing 9 for receiving the pin 4 and with 60 its extremity 10 bent off and having a hole 10^a to receive the band 5, the free end of which may be knotted to effect its engagement with said extremity or arm 10.

11 is the apertured guides or eyelets to be 65 secured to shank 8 in a row. These have basal portions 11^a with respect to which the guides proper are perpendicular and which are flat on their under sides, so that when they rest on the supporting surface therefor 70 (upper surface in Fig. 1) of the shank, as shown, and are secured to such shank they will be proof against tilting and loosening.

The guides are arranged at intervals and at those intervals the lateral edges of the 75 shank are formed with opposite notches 12; in the present example there is only a single notch on each side to correspond with a guide.

For securing the guides in place a cord, 80 string or equivalent flexible element 13 is made to embrace the shank at and so as to engage in the first pair of notches at one end of the series; then its ends are passed inward and through the eye or aperture of the guide; then each is turned back, forming a loop 13^a, and engaged in the same notch which it already occupies; and then the ends are crossed at the other side of the shank and the foregoing operations repeated until all 90 the guides have been threaded and all the notches engaged in this way, when as a final step the ends of the flexible element are cut off and tied and if desired the device is shellaced to stiffen said element and firmly unite 95 its various portions with the shank.

My construction avoids forming, as in the mentioned previous devices of this class, two pairs of holes to receive the cord or the like, one pair on each side of each guide, and it 100 eliminates much of the difficulty in assembling the device in that the manipulation of the cord, etc., requires no threading-through of the cord with respect to (necessarily small holes in) the shank.

105 The guides are held against tilting and therefore working loose by their extended bases 11^a. Another factor insuring their being held firmly is the fact that the portions 13^a of the cord exist as loops which reach inward from points (at the sides of the shank) further apart than the width of

the basal part of each guide aperture (Fig. 5) and so can be made to act against each other in binding the guide in place.

Fig. 6 shows a modification of the extremity 10 of the lever 7, with hole 10^a present; the extremity has been split from its end to the hole and the metal at one side of the split bent out of the plane of the metal at the other side to afford a V-shaped entrance 10^b to the hole. This facilitates engaging the elastic band with the lever: The band can be knotted first and then engaged instead of engaged first and knotted, which latter is always a troublesome operation.

Having thus fully described my invention what I claim and desire to secure by Letters Patent is:

1. A tension lever for a shuttle tension device including, in combination, a shank notched at intervals lengthwise of the same, a plurality of guides arranged along said shank, and flexible attaching means in wrapped engagement with said shank and extending through and binding said guides to said shank and also engaged in the several notches thereof.

2. A tension lever for a shuttle tension device including, in combination, a shank having notches at intervals along the same, a plurality of guides arranged along said shank, the notches being arranged in sides of the shank opposite to each other and relatively lateral of the guides, and flexible attaching means in wrapped engagement with said shank and extending through and binding said guides to said shank and also engaged in the several notches thereof.

3. A tension lever for a shuttle tension device including, in combination, a shank, a plurality of guides arranged along said shank, and flexible means in wrapped engagement with said shank and having pairs

of portions extending through said guides and each pair formed as loops projecting toward each other from sides of the shank relatively lateral of the guides.

4. A tension lever for a shuttle tension device including, in combination, a shank, a plurality of guides arranged along said shank, and flexible means in wrapped engagement with said shank and having pairs of portions extending through said guides and each pair formed as loops projecting toward each other from sides of the shank relatively lateral of the guides, the portions of said means between the loops being arranged at the side of the shank opposed to the guides and arranged to cross each other.

5. A tension lever for a shuttle tension device including, in combination, a shank, a plurality of upstanding guides arranged along said shank and each having a relatively enlarged flat base in contact with the shank, and flexible attaching means in wrapped engagement with said shank and binding the flat bases of said guides against the shank.

6. In a tension lever for a shuttle-tension device having a flat extremity extending from its fulcrum and formed with a hole to receive a knotted rubber band, said extremity having a V-shaped entrance extending from an edge of the extremity to the hole.

7. In a tension lever for a shuttle tension device having a flat extremity extending from its fulcrum and formed with a hole to receive a knotted rubber band, said extremity having a V-shaped slit extending from the edge of the extremity to the hole and the portion at one side of the extremity and at one side of the hole bent out of the plane thereof at the other side of the hole.

In testimony whereof I affix my signature.

FRANCESCO RENZO.
